(57) CLAIM

(22) Filed: **May 13, 1996**

The ornamental design for a exerciser for orifice muscles, as
shown and described.

(51) LOC (7) Cl. **28-03**

DESCRIPTION

(52) U.S. Cl. **D24/211; D24/214**

FIG. 1 is a front elevational view of an exerciser for orifice
muscles, showing my new design with all other sides being
identical to that shown;
FIG. 2 is a top plan view thereof; and,
FIG. 3 is a bottom plan view thereof.
